US0D1005964S

(12) **United States Design Patent** (10) **Patent No.:** **US D1,005,964 S**
(45) **Date of Patent:** **** Nov. 28, 2023**

(54) **ELECTRICAL CONNECTOR**

- (71) Applicant: **Samtec, Inc.**, New Albany, IN (US)
(72) Inventors: **Chadrick Paul Faith**, Corydon, IN (US); **Dale Schmelz**, Depauw, IN (US)
(73) Assignee: **SAMTEC, INC.**, New Albany, IN (US)
(**) Term: **15 Years**
(21) Appl. No.: **29/689,980**
(22) Filed: **May 3, 2019**

Related U.S. Application Data

- (63) Continuation of application No. 29/611,521, filed on Jul. 21, 2017, now Pat. No. Des. 964,291.

(57) **CLAIM**

The ornamental design for an electrical connector, as shown and described.

DESCRIPTION

FIG. 1 is a bottom, right, rear perspective view of an electrical connector showing our new design;

FIG. 2 is a top, left, front perspective view thereof;

FIG. 3 is an enlarged top, right, rear perspective view thereof;

FIG. 4 is an enlarged bottom, left, front perspective view thereof;

FIG. 5 is a bottom plan view thereof;

FIG. 6 is a top plan view thereof;

FIG. 7 is an enlarged right side elevation view thereof;

FIG. 8 is an enlarged left side elevation view thereof;

FIG. 9 is a rear elevation view thereof; and,

FIG. 10 is a front elevation view thereof.

The broken lines in the drawings depict portions of the electrical connector that form no part of the claimed design.

The dash-dot broken lines in the drawings depict the boundaries of the claimed design and form no part thereof.
